UNITED STATES PATENT OFFICE.

ISIDOR SOMMERFIELD, OF NEW YORK, N. Y.

HEEL FOR SHOES.

SPECIFICATION forming part of Letters Patent No. 349,862, dated September 28, 1886.

Application filed June 25, 1886. Serial No. 206,212. (No model.)

To all whom it may concern:

Be it known that I, ISIDOR SOMMERFIELD, of the city, county, and State of New York, have invented certain new and useful Improvements in Heel-Fastenings for Ladies' Shoes and Boots, of which the following is a specification.

This invention relates to an improved heel-fastening for ladies' boots and shoes, by which a strong and reliable connection of the heel with the sole and spring-shanks is obtained, and the breaking off and detaching of the heel prevented; and the invention consists of the combination, with the sole and spring-shank of a boot or shoe, of a heel having a vertical perforation and fastening tongues or anchors, which are passed from the shank through said perforation and bent over the bottom of the heel, so as to connect the heel rigidly to the sole and shank, one of said tongues being cut from the body of the shank.

In the accompanying drawings, Figure 1 represents a side elevation of my improved heel-fastening for shoes, partly in section, through the heel. Fig. 2 is a top view of the heel portion with the insole removed, and Fig. 3 is a bottom view of the heel with a portion of the top lift removed.

Similar letters of reference indicate corresponding parts.

In the drawings, A represents a lady's boot or shoe, B the heel of the same, and C the spring-shank, which is interposed, in the usual manner, between the sole and insole of the shoe. The heel B is made of wood or other suitable material and attached to the sole A by means of fastening tongues or anchors D D, which are passed through a vertical perforation, d, of the heel B. One of the anchors

D is formed integral with the shank by being cut out of the body of the same, while the auxiliary tongues are made of a strip of sheet metal and passed through slots e e of the spring-shank C through the vertical perforation d of the heel to the under side of the same, where the ends of the tongues are bent outwardly and covered by the usual top lift. Besides the tongues connecting the heel with the sole and spring-shank, the usual fastening-screws f are used to attach the heel to the shank and sole. The fastening-tongues D D prevent the breaking off and loss of the heel, as they establish a strong and reliable connection with the body of the heel in addition to the fastening-screws f. The fastening-tongues form, so to say, "anchors" for the heel, by which the same is capable of resisting in a greater measure the strains exerted thereon, the tongues forming a durable and permanent heel-fastening for the shoe.

Having thus described my invention, I claim as new and desire to secure by Letters Patent—

The combination, with a sole and spring-shank, of a heel having a vertical perforation, a tongue or anchor cut from the body of the shank, and auxiliary tongues or anchors that are passed through slots of the shank, all the tongues being passed through the heel and bent over the bottom of the same, substantially as set forth.

In testimony that I claim the foregoing as my invention I have signed my name in presence of two subscribing witnesses.

ISIDOR SOMMERFIELD.
